UNITED STATES PATENT OFFICE.

RAYMOND H. OLLEY, OF SYRACUSE, NEW YORK, ASSIGNOR TO CROUSE-HINDS COMPANY, OF SYRACUSE, NEW YORK, A CORPORATION OF NEW YORK.

LAMP-SHADE, GLOBE, AND GUARD HOLDER FOR CONDUIT-OUTLET BOXES.

Application filed March 19, 1928. Serial No. 262,774.

This invention relates to a combined lamp shade holder, globe and guard for electric lamps and fixtures and has for its object a particularly simple and efficient construction 5 by which the lamp shade holder, globe and the guard are interchangeably mountable on the fixture, the globe interchangeably mountable on the lamp shade holder and the guard, and the guard interchangeably mountable on 10 the lamp shade holder and fixture.

The invention consists in the novel features and in the combinations and constructions hereinafter set forth and claimed.

In describing this invention, reference is 15 had to the accompanying drawings in which like characters designate corresponding parts in all the views.

Figure 1 is a fragmentary side elevation, partly in section, illustrating a lamp shade 20 holder, guard and globe applied to a fixture or base as a conduit outlet box.

Figure 2 is a view similar to Figure 1 showing a lamp shade holder and globe applied to the base or fixture, the guard being omitted.

Figure 3 is a view similar to Figure 1 showing the guard and globe applied to the fixture or base, the lamp shade holder being omitted.

Figure 4 is a view similar to Figure 1 showing the globe applied directly to the base or 30 fixture with the lamp shade holder and guard being omitted.

Figure 5 is an elevation of parts seen in Figure 3, the fixture or base being omitted.

Figure 6 is an end view looking upwardly 35 of the guard shown in Figure 5.

1 designates a base as a conduit outlet box having an opening at one side which is surrounded by a cylindrical flange 2.

3 is a lamp shade holder having a ring 4 40 for interfitting with the cylindrical flange 2 and also having a cylindrical flange 5 of an internal diameter the same as the flange 2.

6 is a lamp guard having a ring 7 fitting the cylindrical flange 5 of the lamp shade 45 holder and hence, also capable of interfitting with the flange 2 of the outlet box interchangeable with the ring 4 of the lamp shade holder, the guard also having a cylindrical flange 8 of the same internal diameter as the flanges 2 and 5 of the outlet box and the lamp shade holder.

9 is a globe having a ring or collar 10 50 interfitting and interlocking with the cylindrical flange 8 of the guard and hence, interchangeably interfitting and interlocking with

the flange 5 of the lamp shade holder, or interfitting and interlocking with the flange 2 of the outlet box interchangeably with the rings 4 and 7 of the lamp shade holder and the guard. 60

11 is a lamp socket mounted in the conduit outlet box within the flange 2, the socket being held in position by a plate 12 which overlies an internal seat 13 at the base of the flange 2 and which may be held in position 65 by any one of the rings 4, 7, and 10 which are interlocked with the flange 2. The flanges and rings are usually threaded with coarse threads.

In Figure 2, the lamp shade holder is 70 shown as mounted on the outlet box and the globe as applied directly to the lamp shade holder.

In Figure 3, the guard 6 is shown as applied directly to the conduit outlet box and 75 the globe is supported by the guard, the lamp shade holder being omitted.

In Figure 4, the globe 9 is mounted directly on the conduit outlet box 1, the lamp shade 80 holder and the guard being omitted.

The guard may be of any suitable form, size and construction, it being in the form of a cage depending from the flange 8 and as having a lower end section 14 detachable for permitting access to the globe to remove 85 it and replace it.

The section 14 is held in position by screws 15 extending through slots formed in lugs 16, in one of the transverse members 17 of the cage, these slots having enlarged portions 90 18 to permit the section 14 to be detached upon partial loosening of the screws and then turning the removable section 14 until the large portions 18 of the slots are in line with the screw heads. 95

Owing to the fact that the rings 4, 7 and 10 of the lamp shade holder, guard and globe are all the same size and capable of fitting the flange 2 of the outlet box, any of these parts can be used to the exclusion of the others 100 and owing to the fact that the flanges 5 and 8 are of the same size as the flange 2 of the outlet box, any combination of the lamp shade holder and/or guard and/or globe can be used with the outlet box 1. 105

What I claim is:

1. The combination of a base having a cylindrical flange, a lamp socket mounted on the base within said flange, a lamp shade holder having a ring for interlocking in the flange, 110

the lamp shade holder also having a cylindrical flange with an internal surface of the same diameter as the cylindrical flange of the base, a guard having a ring for fitting and interlocking with the flange of the lamp shade holder or the cylindrical flange of the base, 5 the guard also having a cylindrical flange formed with an internal surface of the same diameter as the cylindrical flange of the base 10 and a globe having a ring interfitting with the flange of the guard, all whereby the globe, guard and lamp shade holder are applicable interchangeably to the cylindrical flange of the base, and the globe is interchangeably 15 mountable in the flanges of the lamp shade holder and the guard, and the guard is interchangeable mountable in the flanges of the base and the lamp shade holder.

2. The combination of a base having a cylindrical flange, a lamp socket mounted in the base within the flange, a lamp shade holder, a 20 guard and a globe, each having a ring interchangeably mountable in the cylindrical flange and the lamp shade holder and the guard having cylindrical flanges having internal diameters the same as the cylindrical flange of the base, whereby the rings of the globe and of the guard are interchangeably 25 mountable in the flange of the lamp shade holder.

guard having cylindrical flanges having internal diameters the same as the cylindrical flange of the base, whereby the rings of the globe and of the guard are interchangeably mountable in the flange of the lamp shade holder. 30

3. The combination of a base having a cylindrical flange, a lamp socket mounted in the base within the flange, a lamp shade holder, a guard and a globe, each having a ring interchangeably mountable in the cylindrical flange and the lamp shade holder and the guard having cylindrical flanges having internal diameters the same as the cylindrical flange of the base, whereby the rings of the globe and of the guard are interchangeably 35 mountable in the flange of the lamp shade holder, the cylindrical flanges being internally threaded and the rings externally threaded. 40

In testimony whereof, I have hereunto signed my name, at Syracuse, in the county of Onondaga, and in the State of New York, this 8th day of March, 1928.

RAYMOND H. OLLEY.
